UNITED STATES PATENT OFFICE

2,498,409

TOY VEHICLE

Clarence B. Franklin, Inkster, Mich.

Application September 18, 1946, Serial No. 697,677

2 Claims. (Cl. 280—222)

1

This invention relates to a novel construction of multiple use toy vehicle capable of being ridden or driven by one or a plurality of children by a plurality of rider manipulated propelling means.

A primary object of the invention is to provide a toy vehicle capable of being manually propelled by one or more riders by one or a plurality of separately operated propelling means and which is also capable of being steered by one of the riders either while actively engaged in assisting in the propulsion of the vehicle or while riding as a passenger thereon.

Still a further object of the invention is to provide a toy vehicle of the above described character capable of being utilized as a see-saw while immobile or which may be propelled by a see-saw motion of one or two occupants of the vehicle.

Numerous other objects and advantages of the invention will hereinafter become more fully apparent from the following description of the drawings, illustrating a preferred embodiment thereof, and wherein:

Figure 1 is a side elevational view of a toy vehicle constructed in accordance with the invention;

Figure 2 is a sectional view thereof taken substantially along a plane as indicated by the line 2—2 of Figure 1;

Figure 3 is a similar view taken substantially along a plane as indicated by the line 3—3 of Figure 1;

Figure 4 is a longitudinal, substantially central sectional view of the toy vehicle;

Figure 5 is a transverse sectional view taken substantially along a plane as indicated by the line 5—5 of Figure 1;

Figure 6 is a fragmentary longitudinal sectional view of the vehicle taken substantially along a plane as indicated by the line 6—6 of Figure 5;

Figure 7 is a fragmentary plan view of the see-saw or teeter type and totter part of the vehicle;

Figure 8 is a plan view of the vehicle platform with the parts, normally connected thereto, removed;

Figure 9 is a fragmentary sectional view taken substantially along a plane as indicated by the line 9—9 of Figure 3;

Figure 10 is an enlarged horizontal sectional view taken substantially along a plane as indicated by the line 10—10 of Figure 1; and

Figure 11 is an enlarged transverse sectional view taken substantially along a plane as indicated by the line 11—11 of Figure 1.

Referring more specifically to the drawings, the toy vehicle in its entirety is designated generally

10
5

12 and includes an elongated platform 13 which

may be of any desired length and which is sup-

ported in an elevated position and for mobility by

a pair of front wheels 14 and two rear wheels 15

and 16.

As best seen in Figures 2 and 4, the front wheels 14 are journaled on the ends of an axle 17 which is connected to the ends of a steering fork 18, adjacent said wheels 14. The steering fork 18 is provided with a steering post 19 which rises from the upper intermediate portion thereof and which is journaled in a steering column or bearing 20 which is fastened to and which extends through the platform 13, adjacent the forward end thereof. The steering post 19 is retained against accidental displacement from the bearing 20 by a detachable retaining collar and pin fastening 21 which bears against the upper end of the bearing 20. As best seen in Figure 4, the steering post 19 is provided with a longitudinal slot 22 located above the collar and pin fastening 21 and said slotted upper end extends into a downwardly opening socket 23 of a steering and draft tongue 24. The tongue 24 is provided with a cross bar or handle 25 at its upper end, as best seen in Figure 1. The socket portion 23, as best seen in Figures 1 and 2, is provided with opposed depending lugs or wings 26 through which a pin 27 extends. The pin 27 extends through and is loosely disposed in the slot 22 so that by lifting upwardly on the tongue 24 the upper part of the steering post 19 will be disengaged from the socket 23 and swung forwardly so that the tongue can be used for pulling the vehicle 12, or the tongue 24 may be swung rearwardly to rest upon the platform 13 when not in use. By returning the tongue 24 to an upright position and permitting it to move downwardly so that the socket 23 will receive the upper end of the steering post 19, said tongue will be retained in an upright position to be employed in its normal way for turning the axle 17 and front wheels 14 to steer the vehicle 12, since the pin 27 keys the tongue to the steering post 19 so that the former functions as a part of the steering post.

As best seen in Figure 4, the front axle and wheel assembly is preferably braced by means of a diagonal brace 28 which is secured at 29 to the under side of the platform 13 and which extends forwardly and downwardly therefrom and terminates in a horizontal portion which is apertured and which is disposed above the intermediate part of the axle 17. A small fork 30 is secured to the intermediate portion of the axle 17 and is provided with an upwardly extending king

55

pin 31 in the intermediate portion thereof which swivelly engages in the opening of the last mentioned end of the brace 28 for connecting the axle 17 thereto.

As best seen in Figure 3, a substantially U-shaped fork 32 is secured to and depends from the under side of the platform 13 adjacent the opposite end thereof and is disposed transversely of the platform. A rear axle 33 is journaled adjacent its ends in the terminal bearing portion 34 of the fork 32. The wheels 15 and 16 are mounted on the axle 33 on the outer sides of the bearing portions 34. The wheel 15 is fixed to the axle 33 to rotate therewith by a key or spline 35 and the wheel 16 is provided with a bushing 36, disposed between its hub and the axle 33 to rotatably mount said wheel relatively to the axle. A pair of rearwardly and downwardly extending braces 37 are secured at their upper forward ends to the under side of the platform 13 and are provided at their lower, rear ends with bearing portions 38 in which the axle 33 is journaled. The bearing portions 38 are disposed inwardly of and adjacent to the bearing portions 34.

A pair of laterally spaced standards 39 are secured to the platform 13, intermediate of its ends, and said standards extend upwardly therefrom and are provided with upper head portions 40, having aligned openings 41 for receiving a pivot pin 42, preferably in the form of a nut and bolt, as best seen in Figure 5. The standards 39 have out-turned feet portions at their lower ends secured by fastenings 43 to the upper side of the platform 13 and are disposed in upwardly converging relationship and with the head portions 40 thereof disposed in spaced apart, substantially parallel relationship. A see-saw or teeter type and totter bar 44 is disposed lengthwise of the platform 13 and with the intermediate portion thereof positioned between the standards heads 40. Said intermediate portion is provided with an opening 45 through which the pivot pin 42 extends for supporting the bar 44 for oscillating or rocking movement above the platform 13. Said intermediate portion of the bar 44 is provided with a vertically disposed longitudinally extending slot 46, as best seen in Figure 10, for receiving a pair of plates 47 which depend downwardly therethrough and which are provided with arcuate lower edges, as best seen in Figure 4. The plates 47 are provided with out-turned flanges 48 at their upper ends which are secured by fastenings 49 to the upper surface of the bar 44 and by means of which the plates 47 are retained in spaced apart relationship. The plates 47 are likewise provided with openings 50 through which the pivot bolt 42 loosely extends.

The see-saw bar 44 is provided with seats 50 secured on the ends thereof and an arch member 51 is secured to and disposed above the intermediate portion of the bar 44 and is provided with apertured ears 52 to receive handles 53 which extend therethrough and which are positioned to be grasped by the occupants of the two seats 50.

The bar 44 is provided with depending apertured lugs 54 located on opposite sides of its pivoted intermediate portion and each of which is connected to the upper end of a contractile coiled spring 55. The lower ends of the springs 55 are connected to apertured lugs 56 which are secured to and rise from the platform 13, so that said springs 55 tend to act against one another for normally retaining the teeter bar 44 in a horizontal position or parallel to the platform 13.

As best seen in Figures 4 and 5, the platform 13 is provided with a pair of laterally spaced bracket members 57 which depend therefrom and which are disposed intermediate of the ends of the platform and adjacent one side edge thereof. The bracket members 57 are provided with split bearing portions 58 in the lower part thereof and in which a crank shaft 59 is journaled. The shaft 59 is provided with a crank 60 at one end thereof and which is located beneath the central portion of the platform 13 and beneath a longitudinal slot 61 therein. A connecting rod 62 extends through the slot 61 and is provided with a longitudinal slot 63 in its lower part which is loosely engaged by the crank 60. The upper end of the bar shaped connecting rod 62 is loosely disposed between the plates 47 and is provided with an opening 64 through which the pivot bolt 42 loosely extends.

As best seen in Figures 5 and 6, the shaft 59 is provided with a crank 65 located between the bearings 58 and remote to the crank 60 and which is rotatably engaged by a split bearing 66 formed on one end of a connecting rod 67, the opposite end of which is pivotally connected to the lower end of a lever 68 by a pivot 69. The lever 68 extends upwardly through a longitudinal slot 70 in the platform 13 and is fulcrummed on a pivot pin 71 secured in brackets 72 which are fastened to the other side of the platform. The lever 68 as best seen in Figure 5, is provided with an inwardly off-set upper end terminating in a knob or handle 73 which is located adjacent the seat 50 which is remote to the tongue 24, as best seen in Figure 1.

A sprocket wheel 74 is keyed to the crank shaft 59 and a smaller sprocket wheel 75 is keyed to the rear axle 33. An endless sprocket chain 76 is trained over the sprocket wheels 74 and 75 for revolving the rear axle 33 and the rear wheel 15 with the crank shaft 59 and in the same direction and at a greater R. P. M.

As best seen in Figure 5, the plates 57 and connecting bar 62 are provided with openings 77 and 78, respectively, which align when the crank 60 is in a dead center position to receive a locking pin 79 for connecting the rod 62 to the bar 44. As best seen in Figures 1 and 10, one of the heads 40 is provided with an opening 80 to receive a locking pin 81 which extends into a recess 82 in the bar 44 to retain the bar in a horizontal position and to hold it against rocking motion in the standards 39.

The toy vehicle 12, the structure of which has just been previously described in detail, may be employed by one or a number of children in a number of different ways as a play toy. For example, the toy 12 may be ridden and propelled by two children seated upon the seats 50 by removing the pin 81 and by the execution of a see-saw motion to rock the bar 44 to thereby oscillate the connecting rod 62 so that the crank 60 will be rotated to revolve the shaft 59. The crank 60 executes a rotary and sliding motion in the slot 63 as the bar shaped connecting rod 62 is oscillated in the slot 61. It will be readily apparent that this will cause rotation of the sprocket wheel 74 with the shaft 59 to drive the rear axle 33 and the rear wheel 15 to propel the vehicle 12. The occupant of the seat 50 located adjacent the tongue 24 may sit facing the tongue or toward the front so as to steer the front wheels 14 by turning the tongue 24 while at the same time assisting in the teeter-totter motion of the bar 44 to propel the vehicle. Likewise, if desired,

the vehicle may be ridden in the same manner by a single occupant seated on the front seat 50 by utilizing the springs 55 and the momentum of the vehicle to accomplish the upward swinging movement of the forward end of the bar 44. Also, if desired, one or two children may see-saw on the bar 44 by removing both pins 79 and 81 to permit the bar to rock relatively to the connecting rod 62 so that the bar 44 can be utilized as a stationary see-saw rather than a mobile one. By applying the locking pin 81 and removing the locking pin 79, the bar 44 can be rendered stationary and one or more children may occupy the vehicle 12 and be propelled thereon by one or more of the occupants executing a reciprocating pumping operation by engaging the upper end of the hand propelling lever 68 and by swinging said upper end forwardly and rearwardly to cause the connecting rod 67 to be actuated and to actuate the crank 65 for revolving the said crank shaft 59. Also, as previously stated, the tongue 24 may be raised and swung forwardly so that the vehicle 12 may be pulled in the same manner as a toy wagon.

Obviously, the platform 13 may be made in various lengths to afford sufficient space to accommodate one or two or more children in addition to the two children occupying the seats 50 and it will be obvious that while two children propel the vehicle by rocking the bar 44 in a see-saw manner, another child can assist in the propulsion by manually pumping the lever 68.

Various other uses of the vehicle are contemplated and may obviously be employed and various modifications and changes in the structure thereof may likewise be resorted to, without departing from the spirit and scope of the invention as hereinafter defined by the appended claims.

I claim:

1. In an occupant propelled mobile toy, a wheeled platform, a see-saw mounted for oscil-

lating movement thereabove and adapted to support and be actuated by one or a plurality of occupants of the vehicle, and power transmitting and translating means connecting said see-saw to a ground wheel of the vehicle for propelling the vehicle, said transmission means including a crank shaft, a connecting rod slidably and rotatably connected to a crank of the shaft adjacent one end thereof and detachably fixed to the see-saw adjacent its opposite end whereby the connecting rod will be oscillated with the see-saw to revolve the crank shaft.

2. In an occupant propelled mobile toy, a wheeled platform, a see-saw mounted for oscillating movement in a vertical plane thereabove and adapted to support and be actuated by one or a plurality of occupants of the vehicle, and power transmitting and translating means connecting said see-saw to a ground wheel of the vehicle for propelling the vehicle, said transmitting and translating means including a crank shaft, a connecting rod slidably and rotatably connected to a crank of the shaft adjacent one end thereof, said connecting rod being journaled adjacent its opposite end on the pivot of the see-saw, and a pin detachably engaging the connecting rod and see-saw at a point spaced from the pivot of the see-saw to cause the connecting rod to be rocked in unison with the see-saw.

CLARENCE B. FRANKLIN.
